UNITED STATES PATENT OFFICE.

JAMES NORMAN SMITH, OF TORONTO, ONTARIO, CANADA.

ELECTROLYTIC APPARATUS.

Application filed April 7, 1921. Serial No. 459,294.

To all whom it may concern:

Be it known that I, JAMES NORMAN SMITH, a citizen of the Dominion of Canada, residing at Toronto, in the county of York, Province of Ontario, Canada, have invented certain new and useful Improvements in Electrolytic Apparatus; and I do hereby declare the following to be a full, clear, and exact description of the invention, such as will enable others skilled in the art to which it appertains to make and use the same.

This invention relates to the art of electrolysis. More particularly, it relates to apparatus wherein electrolyzing operations can be effected economically and expeditiously at relatively high current densities, while the products of electrolysis can be separately recovered in a state of purity satisfactory for general use. The apparatus may be used, for example, in electrolyzing saline or other solutions, in electrodeposition of metals, and in producing oxygen and hydrogen electrolytically.

Considered broadly, the apparatus of the present invention is of a type generally similar to that described in the co-pending application of Clark & Smith, Serial No. 459,292, filed April 7, 1921, and can be employed in analogous ways and for similar purposes. In the specific illustrative embodiment of the broad invention described in said application of Clark & Smith, a pair of cooperating hollow or tubular electrode members are mounted in axial alignment in opposite walls of a suitable casing or container, the adjacent ends of said tubular electrode members providing annular active electrode surfaces spaced apart only a small distance, usually not more than one-fourth of an inch at the most, and still better as little as one-tenth of an inch or even very much less. In that particular form of apparatus, electrolyte is forced to flow radially inward across the annular slot-like electrolyzing zone thus provided between the electrode members of the couple, at a velocity sufficiently high to prevent substantial intermingling of the anodic and cathodic products in said zone; and as the inwardly flowing body of electrolyte leaves the annular electrolyzing zone, it impinges upon a separator device which is adapted and arranged to divide the inflowing electrolyte into anolyte and catholyte portions, from which anodic and cathodic products

of electrolysis can be separately recovered. Most desirably no porous separating diaphragm is employed, the space between the active electrode surfaces proper being unobstructed.

The present apparatus has some features in common with the construction just described, but involves certain further developments offering substantial practical advantages. One such development is the provision of means whereby the electrolyte travels in separate paths not only after flowing through the electrolyzing zone, but also before it reaches said zone. In a practical embodiment of the present invention, the arrangement may be generally described as comprising separator or partition means having a relatively narrow elongated gap therein adjacent to and in registry with the elongated active electrode surfaces between which the electrolyzing zone is comprised, together with provision for causing electrolyte to flow in the same general direction on both sides of said separator means and across the active electrode surfaces, the flow on both sides of said separator means being substantially parallel through the electrolyzing zone. As in the case of the apparatus disclosed in the aforesaid Clark & Smith application, it is preferred to operate without the use of the usual porous separating diaphragm, the omission of such diaphragm making it possible to bring the active electrode surfaces very close together and thus to greatly reduce the resistance of the current path between the electrodes. The resistance may be still further reduced by operating at relatively high electrolyte temperatures. Where the electrolyte is supplied under pressure, which is often desirable in practice, the operating temperatures may exceed the boiling point of the electrolyte at atmospheric pressure.

For the sake of a concrete example, a practical form of apparatus embodying the broad principles of the invention will be described in connection with the accompanying drawings, in which

Figure 1 is a view in central vertical section of apparatus embodying the invention; and

Figure 2 is a horizontal section on the line 2-2 of Figure 1.

Referring to the drawings, 10 and 11 are sections of a heavy walled casing having

cooperating peripheral flanges 12 between which is clamped the outer marginal portion of an annular separator plate 13 to be referred to more fully hereinafter. The assemblage is held together by any suitable means such as bolts 14 which may be encased in insulating bushings 15; and the joints between the annular plate 13 and the casing flanges are maintained liquid tight by 10 means of suitable packing 16. Mounted in opposite walls of the casing and in axial alignment are cooperating tubular electrodes 17 and 18, 17 being an anode in this instance and 18 a cathode. Each of the electrodes is electrically insulated from the casing wall through which it passes as indicated at 19, and is externally threaded to accommodate nuts 20 and 21, one of which is arranged inside the 15 casing and the other outside, said nuts co-operating to hold the electrode firmly in position while at the same time allowing it to be adjusted in an axial direction.

The adjacent ends of the electrode flare outwardly as indicated, to provide closely adjacent active anode and cathode surfaces 22, 23, which may be substantially plane and parallel, the planes of said annular surfaces being substantially at right angles to the common axis of the two electrodes. 20

Most desirably, said active annular electrode surfaces 22, 23, are very close together, say within one-tenth of an inch of each other or even considerably less. Adjacent the outer periphery of the annular slot-like passage thus formed between the cooperating electrodes of the couple is the inner edge 24 of the annular separator plate 13 before mentioned. It is advantageous to have this inner edge 24 substantially in line with and 25 between the outer peripheral edges of the active electrode surfaces 22, 23. The plate 13 may be of insulating material, as shown; in which case it serves also to insulate the casing sections 10 and 11 from each other and renders optional the employment of insulating material 19 around the electrodes where they pass through the casing walls.

It is also desirable to provide separator means within the tubular electrode assemblage for guiding liquid in separate paths corresponding to those outside said assemblage and communicating respectively therewith through the electrolyzing zone. To this end, a disc 25, composed in this instance of insulating material and having a peripheral separating edge which lies substantially in the plane of the opposed edge of the outer separator member 13, is supported in any suitable manner within the combined tubular electrode assemblage, the disc edge being concentric with the annular active electrode surfaces and substantially in registry with the inner periphery of the active electrode surfaces. In the particular construction here illustrated, the adjacent edges of the

separator members 13 and 25 are shown beveled thin; but while this is desirable, it is not essential to the invention in its broader aspects. It is usually advantageous that the edge upon which the electrolyte flow impinges be fairly thin. This arrangement leaves the annular active electrode surfaces directly exposed to each other, or in other words the passage between them is unobstructed. The disc 25 and the annular plate 13, having the annular opening or gap between their adjacent edges, may be broadly termed separator means, providing separate paths for flow of anolyte and catholyte, respectively, to, through, and away from the narrow electrolyzing zone where the two layeriform bodies of liquid moving swiftly in parallel are momentarily in contact. In the construction here illustrated, the disc 25 is held between conoidal members or heads 26, 27, which curve or taper in opposite directions from the disc 25 into stems 28, which in turn are held in the axis of the electrode assemblage by any suitable means, not shown. It will be seen that the surfaces of these heads diverge gradually from the inner walls of the respective electrode members in a direction away from the electrolyzing zone. In the arrangement here shown, the head 26 has a threaded stud or projection 29 extending through a central aperture in the disc 25, said stud being engaged by a nut 30 of insulating material which is externally threaded for connection to the other head 27. The casing is provided on opposite sides of the plate 13 with discharge outlets 31, 32.

In employing the apparatus above described for the generation of oxygen and hydrogen from water, for example, current at the proper electrolyzing voltage is supplied to the electrodes 17 and 18 in any suitable manner, the electrode 17 being the anode and the electrode 18 being the cathode, and an aqueous electrolyte, such as a solution of caustic soda or caustic potash, may be fed in, preferably under pressure, through both electrodes in the direction of the indicating arrows. Ordinarily the pressure on the electrolyte thus fed in will be the same for both electrodes. The velocity of flow increases gradually owing to the contraction of the annular passages formed between the curved inner walls of the electrodes and the curved surfaces of the deflecting or directing device 25, 26, 27, the contraction being greatest and the maximum velocity therefore being attained where the streams of electrolyte become substantially parallel and flow outwardly through the unobstructed passage between the active electrode surfaces. The width of this annular passage or electrolyzing zone measured parallel to the active electrode surfaces, that is, in the direction of the electrolyte flow, is relatively small; so that

during the brief interval involved in crossing this zone, the rapidly flowing streams or layers of electrolyte do not intermingle perceptibly and the anodic and cathodic products of electrolysis do not interdiffuse materially. Consequently separate flow of anolyte and catholyte, respectively carrying oxygen and hydrogen swept from the active electrode surfaces, is continued and maintained by the action of the dividing edge 24 of the separator plate 13 which the outwardly flowing electrolyte encounters as it leaves the electrolyzing zone. After the electrolyte impinges upon this dividing edge, its velocity of flow immediately falls. Anolyte and oxygen are discharged through outlet 31, while catholyte and hydrogen are discharged through outlet 32. Oxygen and hydrogen may be separated from the anolyte and catholyte, respectively, in any well known or suitable apparatus for this purpose, one suitable type, referred to for the sake of a concrete example but unnecessary to illustrate here, being disclosed in the co-pending application of Clark & Smith aforesaid.

As before stated, the pressure on the electrolyte on both sides of the partition means may be the same. However, under some conditions, or for certain purposes, it may be desirable to operate with greater pressure on one side than on the other. For example, where it is desirable to secure particularly pure oxygen, the pressure on the oxygen and anolyte side may be somewhat greater than on the hydrogen and catholyte side, thus serving further to guard against accidental diffusion of hydrogen in the electrolyzing zone across into the oxygen side. The excess pressure on the oxygen side supplements the natural buoyancy of the hydrogen in the particular arrangement of the apparatus here illustrated, wherein the cathode is disposed above the anode, and the result is production of oxygen having a particularly high degree of purity and freedom from hydrogen.

Instead of having the partition means arranged horizontally as illustrated in Fig. 1, it is sometimes desirable to have such partition means arranged substantially vertically, which can be attained, for example, by turning the apparatus illustrated in Fig. 1 angularly through 90° in the plane of the drawing. When the apparatus is of the specific construction shown, this rotation should be counter-clockwise in order to bring the discharge outlets gas-laden anolyte and catholyte near the upper part of the casing in that position.

It will be noted that while, in above describing the operation of the apparatus, it was specified that the electrolyte was introduced into the electrodes, flowing toward the central portion of the apparatus

and thence outwardly through the electrolyzing zone into the casing, this direction of flow may advantageously be reversed under some conditions, this reversal in direction of flow being permitted by the illustrated arrangement of the apparatus parts. In any case the velocity of the electrolyte diminishes considerably after passage through the electrolyzing zone, thus favoring coalescence of the evolved gas particles into bubbles which can be readily separated from the accompanying anolyte and catholyte, respectively. The ability to dispense with a porous separating diaphragm, coupled with the provision for forcing the electrolyte to flow at sufficiently high velocity across the active electrode surfaces, makes it possible to operate at relatively high current densities. Operation at 10 amperes or more per square inch of projected electrode area, or of the cross sectional area of the current path, is easily attainable without requiring an operating voltage in excess of those commonly employed heretofore in electrolyzing water. The swift flow of electrolyte across the active electrode surfaces sweeps away the fine gas particles as fast as they are generated and thus prevents excessive polarization; while the same agency keeps the active electrode surfaces clean and free from accumulations due to corrosion, and they are therefore effective at all times. The axial adjustability of the electrodes facilitates maintaining the electrodes the proper distance apart for best operation; and it also provides for accurate adjustment between the relative positions of the electrodes and the double separator or partition means whereby proper direction and division of the flowing electrolyte into separate paths is effected. The inner separator device may also be axially adjustable, any suitable mounting thereof that will permit this being appropriate for the purpose, such as that illustrated in the aforesaid application of Clark & Smith.

Another advantage of the present arrangement is that it enables the anolyte and catholyte to be kept circulating in entirely independent systems both within and outside of the generator unit. The commingling of gas-free anolyte and catholyte, and the return of this commingled electrolyte, instead of gas-free anolyte and catholyte separately, to the generator unit for further passage through the electrolyzing zone, is not precluded, however.

Where recovery of the anodic and cathodic products separately is not essential, that portion of the separator means on the effluent side of the electrolyzing zone may be omitted while still realizing the advantages of the invention in part. Other changes in details of construction and ar-

angement may be made without departing from the scope of the broad invention.

Unless otherwise specified, the term annular as employed in the appended claims 5 is to be understood in a broad sense to include not only circular annuli, but other curved annuli, polygonal annuli, and the like. Moreover, it is to be understood that the invention is not limited to apparatus in 10 which the electrodes are annular even in the broad sense mentioned.

The process carried out in the apparatus herein disclosed, is not claimed herein, but is the subject matter of a copending application 15 for patent of Farley G. Clark entitled Method of electrolysis, filed on even date herewith and given Serial Number 459,291.

What I claim is:

20 1. Electrolytic apparatus comprising the combination, with cooperating active anode and cathode surfaces disposed in closely spaced relation and defining an electrolyzing zone of small transverse width measured 25 parallel to said surfaces, of conduit means arranged to direct flow of electrolyte toward, across, and away from said zone in streams which contact with one another only while crossing said zone.

30 2. Electrolytic apparatus comprising the combination, with cooperating active anode and cathode surfaces disposed in closely spaced relation and defining an electrolyzing zone of small transverse width measured 35 parallel to said surfaces, of an electrolyte supply, and means operative to guide flow of electrolyte in separate streams into contact and substantial parallelism with said active surfaces.

40 3. Electrolytic apparatus comprising the combination, with cooperating active anode and cathode surfaces having a free passage between them, of means arranged to conduct separate streams of electrolyte to one 45 side of said passage and to direct said streams across the respective electrode surfaces, and means on the other side of said passage arranged to receive the effluent streams and maintain them separate.

50 4. Electrolytic apparatus comprising the combination, with separator means having an elongated opening or gap therein, of cooperating electrode members disposed on opposite sides of said separator means and in registry with said opening, and means 55 for passing streams of electrolyte on opposite sides of said separator means across said opening between said electrode members.

60 5. Electrolytic apparatus comprising the combination, with separator means having an elongated opening or gap therein, of cooperating electrode members disposed on opposite sides of said separator means and in registry with said opening, and means 65 for forcing electrolyte to flow rapidly in the

same general direction on opposite sides of said separator means and in parallel across said opening between said electrode members.

6. Electrolytic apparatus comprising the 70 combination, with separator means having an elongated opening or gap therein, of cooperating electrode members disposed on opposite sides of said separator means and in registry with said opening, and means for forcing electrolyte to flow rapidly in the 75 same general direction on opposite sides of said separator means and in parallel across said opening between said electrode members, the relative positions of said electrodes and separator means being adjustable.

7. Electrolytic apparatus comprising the combination, with cooperating annular anode and cathode surfaces spaced apart to 85 provide an annular passage, of conduit means arranged to direct electrolyte through said passage and across the electrode surfaces in substantially parallel streams.

8. Electrolytic apparatus comprising the 90 combination, with cooperating annular anode and cathode surfaces spaced apart to provide an annular passage, of conduit means arranged to direct electrolyte through said passage and across the electrode surfaces in substantially parallel streams, and conduit means arranged to receive said parallel streams as they leave said passage.

9. Electrolytic apparatus comprising the 100 combination, with a casing, of cooperating tubular electrode members coaxially mounted in opposite walls of said casing and having their inner ends closely adjacent but spaced apart to provide an annular electrolyzing zone, a separator device mounted centrally with the assembled electrode members and having tapered portions extending oppositely from the vicinity of said zone into said electrode member, between each of which tapered portions and the inner wall 105 of the corresponding electrode member is formed an annular conduit which is constricted adjacent said electrolyzing zone, the two conduits thus formed curving radially outward and merging substantially at the inner periphery of said electrolyzing zone, an annular separator device having its inner periphery located substantially at the outer periphery of said electrolyzing zone and substantially in the same plane as the merger line of said conduits, and conduit means opening into said casing on opposite sides of said partition device.

10. Electrolytic apparatus comprising the 115 combination, with a casing composed of cooperating flanged sections, of cooperating tubular electrode members coaxially mounted in opposite walls of said casing, the inner ends of said electrode members being 120 flared and closely adjacent but spaced apart 130

to provide an annular electrolyzing zone, a separator device mounted centrally within said electrode members and having a thin peripheral edge located intermediate the same and closely adjacent the inner periphery of said zone, said separator device tapering in opposite directions from said edge and forming with the inner walls of the respective electrode members annular conduits which narrow toward said edge, an annular partition marginally clamped between the flanges of the casing sections, the thin inner periphery of said partition being closely adjacent the outer periphery of said zone and in substantially the same plane as the said peripheral edge of said separator device, and separate conduits opening into said casing on opposite sides of said partition.

20 11. Electrolytic apparatus comprising the combination, with cooperating electrodes having surfaces disposed in closely spaced

relation and defining an electrolyzing zone between them, of guiding walls cooperating with said electrodes to direct flow of electrolyte in a plurality of streams to and across said electrolyzing zone. 25

12. Electrolytic apparatus comprising the combination with cooperating electrodes having active electrode surfaces disposed in closely spaced relation and defining an electrolyzing zone between them, of two conduit means on one side of said electrolyzing zone arranged to direct flow of electrolyte in two separate streams to said electrolyzing zone 30 and in substantial parallelism across said zone, and two conduit means on the opposite side of said zone arranged each to receive one of said streams of electrolyte and to deliver the same from said apparatus. 35 40

In testimony whereof I hereunto affix my signature.

JAMES NORMAN SMITH.
